UNITED STATES PATENT OFFICE

160,090

PHOTOGRAPHIC ENLARGER

Mark T. Kolesnikoff, Los Angeles, Calif.

Application October 28, 1949, Serial No. 5,746

Term of patent 14 years

(Cl. D61—1)

To all whom it may concern:

Be it known that I, Mark T. Kolesnikoff, a citizen of the United States, residing at Los Angeles, county of Los Angeles, and State of California, have invented a new, original, and ornamental Design for a Photographic Enlarger, of which the following is a specification, reference being had to the accompanying drawing, forming part thereof.

The figure is a side perspective view of a photographic enlarger, showing my new design, the opposite side presenting substantially the same appearance as the side shown.

I claim:

The ornamental design for a photographic enlarger, substantially as shown and described.
MARK T. KOLESNIKOFF.
